THOMAS BRADY, OF EAST ORANGE, NEW JERSEY, ASSIGNOR TO OTIS ELEVATOR COMPANY, OF NEW YORK, N. Y., A CORPORATION OF NEW JERSEY

ELEVATOR GUIDE

Application filed April 12, 1930. Serial No. 443,831.

The invention relates to guides and particularly to guides for the movable bodies of elevator installations.

In the elevator art it is desirable to provide guides on the elevator car and counterweight for cooperating with guide rails in the hatchway to guide the car and counterweight in their movement in the hatchway. It is also desirable to reduce the friction and wear arising from contact of the guides with the guide rails upon movement of the car and counterweight. The application of lubricant to the guide rails is found helpful in reducing such friction.

In the event of misalignment of the guide rails, or rocking or canting of the car, it may be desirable to lessen the friction by other means. This may be effected, for example, by employing flexible guides in which the surfaces of the guides are maintained in yielding contact with the guiding surfaces of the rails and in which the pressure of the guides against the rails is distributed substantially uniformly over the contacting surfaces. The present invention is directed to such flexible guides.

A feature of the present invention is a flexible guide, for a movable body of an elevator system, having a plurality of independent guide members for cooperating with the guiding surfaces of the guide rail with which the guide is associated.

A second feature resides in maintaining a guide member, of a guide carried by a movable body, in yielding engagement with one of the guiding surfaces of the guide rail for the body independently of other similar guide members of the same guide which cooperate with the other guiding surfaces of the guide rail.

A third feature is the provision of a rotatable guide member which is yieldingly maintained in rolling engagement with one of the guiding surfaces of a guide rail.

A fourth feature is a flexible guide having a plurality of independent rotatable guide members which are independently biased into rolling engagement with the guiding surfaces of a guide rail.

Other features and advantages will become

apparent from the specification, taken in connection with the accompanying drawings wherein one embodiment of the invention is illustrated.

The invention will be described as employed for guiding an elevator car in its movement in the elevator hatchway. According to the embodiment of the invention to be described, a pair of T-shaped guide rails, extending throughout the height of the hatchway, are provided for the car. Guides, mounted at each end of the top and bottom cross members of the car sling, are arranged to cooperate with the guide rails to guide the car in its movement in the hatchway. Each guide comprises a plate having a slot into which the guiding portion of the guide rail extends. A pair of lugs are formed on the plate at opposite sides of the slot and a third lug is formed on the plate at the end of the slot. A bell crank is pivotally supported by each lug and carries a roller for engaging one of the guiding surfaces of the guide rail. A spring associated with each bell crank biases the corresponding roller into rolling engagement with the guide rail. The arrangement is such that each spring maintains the corresponding roller in yielding engagement with the guide rail so that there is substantially uniformly distributed pressure on any contacting surfaces at all times irrespective of any irregularities that may exist in the alinement of the guide rail. In the event of misalignment of the guide rail, the roller which passes over the point of displacement moves relatively to the guide plate to compensate for the irregularity without transmitting a shock to the elevator car. Also, canting or rocking of the car, such as might result from uneven distribution of the load in the car, is compensated for by movement of the bell cranks, toward or away from the guide rails about their pivots, so as to maintain the guide rollers in contact with the guide rails at all times. Thus a substantially constant pressure of the guide rollers is obtained, minimizing friction and wear and the possibility of gouging of the guide rails. Suitable stops are also provided on the plate for limiting the movement of

the bell cranks and rollers by or against the force of their biasing springs.

In the drawings:—

Figure 1 is a schematic view of an elevator installation showing an elevator car embodying the guiding means of the present invention;

Figure 2 is an enlarged plan view of one of the guides, which is shown in cooperative relation with the guide rail;

Figure 3 is a front view of the guide shown in Figure 2, the guide rail being omitted but the guide rollers being shown spaced to receive the rail; and

Figure 4 is an enlarged side view of one of the guides carried by the car, the guide rail also being shown.

Referring to Figure 1, the numeral 21 designates an elevator car carried by a car sling 22 to which hoisting roping is secured for raising and lowering the car in the hatchway. Guide rails 24 for the car are provided in the hatchway. The guide rails shown are T-shaped and have side surfaces 25 and an end surface 26 for cooperation with guides 27, mounted on the upper and lower cross members of the car sling, to guide the car in its movement in the hatchway. As the guides 27 are of identical construction only a single guide and the operation thereof will be described in detail.

Referring to Figures 2, 3 and 4, a plate 30 secured to the car sling 22 is provided with a slot 31 into which the guide rail extends, clearances being provided between the side and end surfaces of the guide rail and the sides of slot 31. A pair of lugs 32 are formed on plate 30 and are located preferably in facing relation, at opposite sides of slot 31. The lugs 32 support studs 34 which extend through openings in the bifurcations 35 of the arms 36 of bell cranks 37 and serve as pivots for the bell cranks. Studs 40, supported by the bifurcations 35, constitute stub shafts 45 on which non-metallic rollers 41, positioned between the bifurcations, are rotatably mounted. The rollers 41 are provided with suitable bushings 39. Springs 43 mounted between bosses on plate 30 and adjustable stops 45, carried by angular portions 46 of the bell cranks, act to bias the rollers 41 into yielding engagement with the side surfaces 25 of the guide rail. Studs 47, passing freely through the bell cranks, are threaded into plate 30. The studs 47 are threaded throughout their length and are provided with nuts 48 and 50 which serve as stops for limiting the movement of the bell cranks by and against the force of their springs.

A lug 51 formed on plate 30 at the end of slot 31 supports a bell crank 52 carrying a roller 53 for engaging the end surface 26 of the guide rail. Bell crank 52 is also provided with a biasing spring 54 and limit stops, the arrangement being similar to that of the bell

cranks 37 in all respects except that the bell crank 52 does not have an angular portion.

The operation is as follows: The springs 43 maintain the rollers 41 in engagement with the guiding surfaces 25 of the rail and spring 70 54 biases the roller 53 into engagement with the end guiding surface 26 of the rail. Upon movement of the car, the rollers roll along the guiding surfaces of the rail to guide the car in its movement in the hatchway. In the event that, at any point in its length, the 75 guide rail is displaced from proper alignment, the rollers move relatively to guide plate 30 to compensate for the misalignment of the rail as their supporting bell cranks 80 pivot on the guide plate. Assume, for example, that the displacement of the guide rail is in the direction of the arrow A in Figure 2. When the rollers pass over the point at which the rail is displaced, the bell crank 85 37 carrying the roller 41 engaging the guiding surface 25 in the direction of displacement moves clockwise compressing the associated spring while the spring associated with the bell crank 37 carrying the roller 41 90 engaging the opposite guiding surface 25 acts to turn the bell crank for maintaining the roller in engagement with the guiding surface of the rail. Thus, both rollers are maintained in proper engagement with the rail. 95

In the event that the guide rail is displaced endwise, for example in the direction of the arrow B in Figure 4, the roller 53 moves relatively to plate 30 to compensate for the misalignment. As the roller 53 passes over the 100 point of displacement, the bell crank 52 moves about its pivotal mounting, compressing the spring 54. Such movement of bell crank 52 permits roller 53 to yield so that proper rolling engagement with the end guiding surface is maintained.

It is to be noted that with the rollers yielding in this manner as they pass over a joint in the rails where a misalignment exists no shock is transmitted to the car.

The bell cranks carrying the guide rollers also move relatively to the guide plates to compensate for rocking or canting of the car, such as might be caused by an uneven distribution of the load in the car. As a 115 result, the guide rollers are maintained in rolling engagement with the guiding surfaces of the guide rail at all times to insure proper guiding of the car.

Each of the biasing springs for the rollers 120 maintains its respective roller in engagement with the guide rail independently of the other guide rollers and the movement of each roller supporting bell crank, by or against the force of the respective biasing spring, to 125 compensate for irregularities is independent of the movement of the other bell cranks. Moreover, the pressure with which the guide rollers are maintained in contact with the guide rail is evenly distributed over the con- 130

tacting surfaces. Thus, the movement of the bell cranks to compensate either for irregularities in the alignment of the guide rails, or rocking or canting of the car as above 5 described, minimizes friction and wear of the contacting surfaces of the guide rails and guide rollers.

Although the limit stops are shown as adjusted to provide a clearance between the 10 stops and bell cranks for permitting movement of the roller supporting bell cranks in either direction relatively to plate 30 to compensate for irregularities in the alignment of the guide rails, it is to be understood that 15 other adjustments of the stops may be made if desired. For example, stops 48 may be adjusted so that there is normally no clearance between these stops and the bell cranks and so that a slight clearance is provided between the rollers and the guiding surfaces of the rail. In the event of irregularities in the 20 guide rail or lateral movement of the car with this arrangement, one or more of the rollers engage the corresponding guiding surfaces 25 and, being rotatably mounted, guide the car with a minimum of friction. The bell cranks carrying these rollers may also move against the force of the biasing springs to compensate for irregularities in the rail or lateral 30 movement of the car.

Although the guide rollers have been described as being non-metallic, it is to be understood that metallic rollers may be employed if desired. The guide rollers may, if 35 desired, be provided with sound deadening means, such as solid or pneumatic rubber tires. Suitable roller bearings and lubricating devices therefor may also be provided to insure easy and quiet operation of the 40 guide rollers as the car moves in the hatchway.

The application of a lubricant, such as oil, to the guide rails is rendered unnecessary by the employment of roller guides carried by 45 the car. This factor causes the roller guides to be particularly suitable for use in high buildings, and is also of advantage in connection with the operation of safety mechanism carried by the car and cooperating with 50 the guide rails to bring the car to rest under emergency conditions. Inasmuch as it is unnecessary to lubricate the guide rails, the effectiveness of the safety mechanism is increased since the safety jaws, or other elements of the safety mechanism which are 55 arranged to cooperate with the guide rails, do not have to cut through a film of lubricant on the rails in order to stop the car.

As many changes could be made in the 60 above construction and many apparently widely different embodiments of this invention could be made without departing from the scope thereof, it is intended that all matter contained in the above description or 65 shown in the accompanying drawings shall be

interpreted as illustrative and not in a limiting sense.

What is claimed is:

1. In an elevator installation; a hatchway; a body movable therein; a guide rail in said hatchway for said movable body; a support carried by said body; a plurality of rollers, one for each of the guiding surfaces of the guide rail, said rollers rolling upon their respective guiding surfaces to guide said body 70 in its movement in said hatchway; a support for each roller, said supports being pivotally mounted on said first named support; and a spring for each of said rollers, said springs acting through said supports to maintain 75 their corresponding rollers in yielding rolling engagement with said guiding surfaces.

2. In an elevator installation; a hatchway; a body movable in said hatchway; a guide rail in said hatchway for said body, said 80 guide rail having oppositely disposed side guiding surfaces and an end guiding surface; a guide roller for each guiding surface; a bell crank for each roller, said bell cranks rotatably supporting their respective rollers; 85 a guide plate carried by said body, said guide plate having a slot into which said guide rail extends; a plurality of lugs on said plate, one for each of said bell cranks, said lugs being disposed adjacent the sides of said slot; 90 means for pivotally connecting one arm of each of said bell cranks to the lug for that bell crank; and a plurality of springs, one for each bell crank, said springs being positioned between the other arms of their respective bell cranks and said plate for biasing said rollers into rolling engagement with 95 their respective guiding surfaces.

In testimony whereof, I have signed my name to this specification.

THOMAS BRADY.
